UNITED STATES PATENT OFFICE.

JOHN G. BAINBRIDGE, OF NEW YORK, N. Y.

DESIGN FOR A SPONGE-CUP.

SPECIFICATION forming part of Design No. 21,589, dated May 31, 1892.

Application filed April 21, 1892. Serial No. 430,128. Term of patent 14 years.

To all whom it may concern:

Be it known that I, JOHN GEORGE BAINBRIDGE, of the city and county of New York, in the State of New York, have invented and
5 produced a new and original Design for a Cup, of which the following is a specification, referred to the accompanying drawings, forming a part thereof, in which—

Figure 1 represents a side view of a cup of
10 my design, and Fig. 2 an inverted plan view of the same.

The leading features of my design are a

polygonal base B and a body A, of circular horizontal contour, the sides of which project directly over the said base, as shown at a in the drawings.

What I claim is—

The design for a cup, as herein shown and described.

JOHN G. BAINBRIDGE.
